UNITED STATES PATENT OFFICE.

HERMAN C. HIRSCHY, OF DULUTH, MINNESOTA.

DESIGN FOR A WASHING-MACHINE.

59,748.

Specification for Design.

Patented Nov. 22, 1921.

Application filed April 22, 1921. Serial No. 463,680. Term of patent 14 years.

To all whom it may concern:

Be it known that I, HERMAN C. HIRSCHY, a citizen of the United States, resident of Duluth, in the county of St. Louis, State of Minnesota, have invented a new, original, and ornamental Design for Washing-Machines, of which the following is a specification, reference being had to the accompanying drawing, forming a part hereof.

The figure is a front elevation of a washing machine showing my new design.

I claim:

The ornamental design for a washing machine, as shown.

HERMAN C. HIRSCHY.
